UNITED STATES PATENT OFFICE.

WALTER FIFTAL, OF WATERBURY, CONNECTICUT.

INTERCHANGEABLE-JAWED TOOL.

1,338,005.

Specification of Letters Patent.

Patented Apr. 27, 1920.

Application filed January 25, 1919. Serial No. 273,028.

To all whom it may concern:

Be it known that I, WALTER FIFTAL, a citizen of Austria, residing at Waterbury, county of New Haven, and State of Connecticut, have invented certain new and useful Improvements in Interchangeable-Jawed Tools, of which the following is a specification.

This invention relates to improvements 10 in mechanics' tools of the type used in cutting, piercing or gripping miscellaneous articles.

The principal object is to provide a tool 15 having interchangeable jaws which may be readily engaged or disengaged with the handle, thereby providing a plurality of miscellaneous tools adapted to be operated by a common handle.

A further object is to provide a plurality 20 of perforating punches and dies arranged upon rotatable disks pivotally engaged at the ends of the jaws in such manner that a variety of holes may be pierced with a single tool, a gage being provided to guide 25 the material so that the holes may be pierced with exactitude.

These and other like objects, which will 30 become more fully manifest as the description progresses, are attained by the novel construction and combination of parts hereinafter described and shown in the accompanying drawings, forming a material part of this disclosure, and in which:—

Figure 1 is a side elevational view of the 35 preferred form of the tool having a pair of jaws containing rotatable disks, provided with punches and dies for piercing round holes and having an adjustable guide, by means of which the holes may be equally 40 spaced from an edge, and,

Fig. 2 is a fragmentary side elevational 45 view showing means for holding the disk spindle in an assembled position.

Fig. 3 is a detail view of a slotted bar and adjusting screw.

The drawing shows pairs of plain jaws 40 and 41, the former carrying at its recessed outer end a tubular rivet 42, upon which is a rigidly mounted disk 43 having a plurality 50 of uniformly spaced recesses 44 in their sides, engageable with which is a pin

45 attached to the free end of a spring plate 46, secured by screws 47 to the jaw 40.

Engaged in the periphery of the disks, between the recesses 44, are screw threaded 55 dies 48 the same being substantially cylindrical and containing openings entering the tubular rivet 42, so that the punchings are readily removed.

In the opposite jaw 41 is another disk 48 60 provided with like openings 44, engageable with pins in the manner before mentioned and set in the periphery are punches 49 corresponding to the openings in the several dies 48. Thus as the jaws are operated so 65 as to cause the disks to approach each other, any material placed between will be perforated, and in order to secure suitable guiding means so that the perforations will be uniformly spaced from the edge, a bent bar 70 50 is secured by a screw 51 as shown in detail in Fig. 3, passing through a longitudinal slot therein so that the guide may be adjusted as desired.

As shown in Fig. 2, the stud 53 is formed 75 with an annular recess 54 in which is engaged a hook-like element 55 pivoted by the screw 56 upon the shank 41, and it will be obvious that by moving the elements 55 outwardly the stud may be released so as 80 to pass through the opening formed in the end of the jaw permitting another disk to be entered.

From the foregoing it will be seen that a 85 conveniently operated device for piercing holes has been disclosed, which may be operatively engaged with the handle levers, as may also the several other jaws shown, thereby forming a very convenient and complete implement for mechanical purposes. 90

Having thus described my invention, what I claim as new and desire to secure by Letters Patent, is:—

In a tool of the character described having a handle and jaws pivotally secured 95 thereto and to each other, the combination of a pair of oppositely disposed disks having a plurality of uniformly spaced recesses, secured to the outer ends of said jaws, spring plates secured in the recesses of said disks 100 and to said jaws, screw-threaded dies containing openings engaged in the periphery

2

of one of the disks, a tubular rivet at each jaw in communication with said openings of said dies, and a bent bar secured to the inner side wall of one of said jaws, punches set in the periphery of the opposite die corresponding to the openings in the dies of the opposite disk, said bar having a longi-

tudinal slot, and a set screw adjustable in said slot for guiding the material to be operated on between the jaws, substantially as 10 described.

In testimony whereof I have affixed my signature.

WALTER FIFTAL.
